UNITED STATES PATENT OFFICE.

CLAYTON TRIDLE ULREY, OF EAST ORANGE, NEW JERSEY, ASSIGNOR TO WESTINGHOUSE LAMP COMPANY, A CORPORATION OF PENNSYLVANIA.

ELECTRON DEVICE ADAPTED FOR HIGH POTENTIAL.

Application filed November 28, 1922. Serial No. 603,724.

This invention relates to electron or X-ray devices and more particularly to such devices so constructed that a reduction of the electrical stresses in the walls of the envelopes thereof is effected.

An object of my invention is to so construct electron-devices, for example, X-ray tubes, that severe electrical stresses, tending to puncture the walls of such devices, when high voltage is applied during operation, will not develop.

Another object of my invention is the construction of envelopes for electron devices, with a conductive film or coating on the outside of the cathode end thereof and connected to the cathode, whereby a difference in potential between the inner and outer surfaces of the envelope is prevented from building up to a dangerous extent.

20 A further object of my invention is the prevention of the accumulation of negative electric charges on the interior of the envelope of the electron device, to such an extent as to cause rupture of the material comprising the envelope.

A still further object is the provision of envelopes for electron devices, so constructed that punctures are avoided when a high potential is impressed thereon.

30 Other objects and advantages of the invention will be apparent upon reading the following detailed description.

It is well known that the envelopes of high voltage electron devices, such as X-ray tubes, are subject to puncture when in operation. Punctures from electrical discharge usually occur in the cathode or negative end of the tube. The possible explanation of this phenomenon is that the inside surface of 40 the envelope becomes negatively charged by electrons coming directly from the cathode or by the secondary or reflected electrons from the anode or target of the device.

The influence of the electrodes is such as to 45 cause a denser charge in the cathode end than in the anode end of the tube. Such a negative charge on the inside of the tube will cause the outside surface thereof to become positively charged by electrostatic induction especially since the surrounding air is ionized by X-rays. The charges accumulate on the opposite surfaces of the glass until the same is broken by the electrostatic stress developed therein.

The above explanation is for the simple 55 case of a high vacuum, high voltage X-ray tube with a hot cathode and operated from a source of direct current. A tube operated on alternating current will stand a higher 60 crest voltage than it will when operated on direct current, because the time interval between pulses is sufficient to allow the electrical stress to be relieved by leakage.

According to my invention I prevent electrical stress of such intensity as to cause 65 puncture in X-ray tubes or other electron devices by either neutralizing the effect of the negative charge on the interior of the tube, preventing the accumulation of such negative charge or making the walls of the 70 tube where such negative charge occurs of sufficient thickness to safely resist the same.

My invention will be better understood by referring to the accompanying drawing in which,

75 Fig. 1 represents a high voltage X-ray tube constructed according to my invention; and

Figs. 2 and 3 represent tubes constructed according to modification of my inventive 80 idea.

The evacuated tube 6 (Fig. 1), may be formed of glass or other transparent insulating material and, as shown, may comprise a main substantially spherical compartment 85 7, a relatively short substantially cylindrical extension 8 and a relatively long substantially cylindrical extension 9 extending in the opposite direction from the extension 8. An electron emitting cathode 11 is preferably sealed into the short extension 8 and a target or anode 12 may be sealed into the extension 9, forming a complete X-ray tube.

The short cylindrical extension 8 and the cathode portion of the main compartment 7 95 may be coated with a conductive film 13, as shown, which is in electrical contact with the cathode 11. The film 13 may be extended to cover a half or more of the main compartment and may be applied in any desired 100 manner, for example, the tube may be painted with metallic paint, such as aluminum enamel, or may be coated with tinfoil or other metallic or conducting foil. The conducting coating 13 obviously shortens the 105 effective length of the tube for insulating purposes and for this reason the anode extension 9 is made unusually long so that the

effective length of the tube, that is, from the termination of the conductive film on the main compartment 7, to the portion of the tube where the anode is sealed therein, is sufficient to provide proper insulation for the high voltage used on the tube. When such voltage is impressed between the anode and cathode, the cathode being heated to an electron-emitting temperature from any suitable source or electrical energy (not shown), an electron stream is emitted therefrom, part of which impinges on the anode to develop X-rays.

Substantially all of the electrons emitted in the general direction of the anode are believed to be drawn thereto and prevented from striking the walls of the tube adjacent said anode. However, stray electrons appear to accumulate on the inner surface of the walls at the cathode end of the tube.

If it were not for the conducting film 13 on the outer surface of said cathode end, said electrons forming a negative charge on said inner surface, would induce a corresponding positive charge on the outer surface of said tube, thereby placing the glass therebetween under electric stress, depending on the intensity of the accumulated charges.

Coating the exterior of the tube at the cathode end, not only prevents a large potential difference from developing between the inner and outer surfaces of the glass by providing a negative charge corresponding to the negative charge developed on the interior of the glass, but tends to prevent any negative charge from forming on said inner surface of the glass because of the well known repelling action of like charges. That is, by reason of said negatively charged conductive coating on the exterior of the cathode end of the tube, the harmful effect of a possible negative charge on the interior surface of the tube is not only prevented, but said charged outer coating exerts a directing influence on the stream of electrons from the cathode because of its repelling effect and therefore has the effect of causing a greater proportion of electrons to be thrown on the anode or target of the device.

The device shown in Fig. 2 comprises an envelope 14, which may be of conventional form and contain a cathode 15 and an anode 16 as shown. The cathode in this case is provided with a directive conducting shield 17 as shown, formed of material substantially transparent to X-rays, for example, aluminum, opening toward the anode and closed in other directions whereby the electrons emitted from the cathode are intercepted by said shield, except those which travel in the general direction of the target 16. The shield preferably extends to partly surround the anode as shown, so as to intercept electrons reflected from the anode. In this way, an electron or negative charge is prevented from

building up on the interior of the X-ray tube and a conductive coating on the exterior thereof is not necessary.

The device shown in Fig. 3 may comprise a tube 18 of conventional form containing a cathode 19 and an anode 21 of any usual type. The wall 22 of the main portion 23 of the tube adjacent the cathode end and part of the cathode extension is thickened considerably, as shown, whereby it is adapted to resist a considerably greater electric stress than ordinarily.

The coating 13 in Fig. 1, if extended into the path of the X-rays, the shield 17 in Fig. 2 and the thickened glass wall 22 in Fig. 3 will naturally exert a filtering action on X-rays passing therethrough and will absorb the softer rays, to some extent, even though made of material substantially transparent to X-rays. This result is not undesirable, as filters are used for such purpose with X-ray tubes operated on high voltage.

Although I have disclosed what I now consider to be the preferred embodiments of my invention, it is to be understood that the same are merely illustrative, that my invention is adapted for application to other electron devices besides X-ray tubes and is only limited by the spirit and scope of the appended claims.

What is claimed is:

1. An X-ray tube of the high voltage type comprising an envelope having cathode and anode arms extending outwardly therefrom, an electron-emitting cathode supported by one arm and an anode supported by the other arm, and an electrically conductive material covering the cathode arm and a portion of the envelope, said material being intimately united to said cathode, whereby said material becomes negatively charged during the operation of said tube and thereby prevents any accumulation of electrons on the interior surface of the envelope and exerts a directive influence on the stream of electrons flowing between said cathode and anode.

2. An X-ray tube of the high voltage type comprising an envelope having cathode and anode arms extending outwardly therefrom, an electron-emitting cathode supported by one of said arms and an anode supported by the other of said arms, one of said arms being materially longer than the other arm, and an electrically conductive material covering the cathode arm and a portion of the envelope, said material being intimately united to said cathode, whereby said material becomes negatively charged during the operation of said tube and thereby prevents any accumulation of electrons on the interior surface of the envelope and exerts a directive influence on the stream of electrons flowing between said cathode and anode.

3. An X-ray tube of the high voltage type comprising an envelope having cathode and anode arms extending outwardly therefrom, an electron-emitting cathode supported by one arm and an anode supported by the other arm, and a coating covering the cathode arm and a portion of the envelope, said material being intimately united to said cathode, whereby said material becomes negatively charged during the operation of said tube and thereby prevents any accumulation of electrons on the interior surface of the envelope and exerts a directive influence on the stream of electrons flowing between said cathode and anode.

4. An X-ray tube of the high voltage type comprising an envelope having cathode and anode arms extending outwardly there-

from, an electron-emitting cathode supported by one of said arms and an anode supported by the other of said arms, one of said arms being materially longer than the other arm, and a coating covering the cathode arm and a portion of the envelope, said material being intimately united to said cathode, whereby said material becomes negatively charged during the operation of said tube and thereby prevents any accumulation of electrons on the interior surface of the envelope and exerts a directive influence on the stream of electrons flowing between said cathode and anode.

In testimony whereof, I have hereunto subscribed my name this 27th day of November, 1922.

CLAYTON TRIDLE ULREY.
